RACK FOR HOLDING TWIST DRILLS

Frank L. Johnson, Brattleboro, Vt.

Application July 10, 1933, Serial No. 679,786

2 Claims. (Cl. 211—69)

This invention appertains to tool holders or racks and more particularly to a novel device for holding a set of different sized twist or like drills.

5 One of the primary objects of my invention is to provide an improved rack or holder for a set of different sized drill bits with novel means forming a part of the rack or holder for permitting the convenient selection and grasping of 10 any desired drill bit.

Another important object of my invention is 15 the provision of a drill holder or rack embodying a plurality of pivoted sockets for receiving the different sizes of drills with means consisting of spring pressed keys for engaging and operating any one of the sockets to move the same to an elevated position out of alignment with the other sockets whereby the drill can be conveniently taken from its socket.

20 A further important object of my invention is the provision of resilient means carried by the rack or holder for engaging the sockets and for holding the sockets against accidental movement either in their raised vertical position or in their 25 lowered horizontal position.

A still further object of my invention is to provide an improved holder or rack for drills of the above character which will be durable and efficient in use, one which will be simple and easy 30 to manufacture, and one which can be placed upon the market at a reasonable cost and readily carried in a tool chest or case.

With these and other objects in view, the invention consists in the novel construction, arrangement and formation of parts, as will be hereinafter more specifically described, claimed, and illustrated in the accompanying drawing, in which drawing:

40 Figure 1 is a fragmentary top plan view of my improved drill holder or rack showing parts thereof broken away and in section.

Figure 2 is a transverse section through my improved drill holder or rack showing one of the drill sockets in its elevated position for permitting the removal of the drill therefrom.

45 Figure 3 is a similar view showing the drill socket in its normal position, and

Figure 4 is an enlarged detail sectional view 50 showing the top wall of the case or rack with the guide opening therein for one operating key of a drill socket.

55 Referring to the drawing in detail, wherein similar reference characters designate corresponding parts throughout the several views, the letter A generally indicates my improved drill

bit holder or rack which comprises a longitudinally extending flat bottom wall 10, which can be formed of sheet metal of the desired gage, if preferred. Arranged in spaced relation to the bottom wall 10 is a top wall 11, which can likewise be formed of sheet metal of the desired gage, if preferred. The bottom and top walls 10 and 11 are connected together by side walls or blocks 12 and it is to be noted that the top wall 11 terminates slightly short of the front edge of 10 the bottom wall 10, for a purpose, which will be later described.

Extending longitudinally of the holder or rack is a pivot shaft 13, which shaft is located substantially equidistantly from the bottom and top 15 walls 10 and 11 and forwardly of the front edge of the top wall 11. This pivot shaft 13 has its ends anchored in the side walls or blocks 12 adjacent to the front ends thereof. Rockably mounted on the pivot shaft 13 is a plurality of 20 sockets 14 for receiving the different sizes of drill bits 15. These sockets are provided with flat inner walls 16, for a purpose, which will be later described. It is to be also noted that each socket 14 carries a leaf spring 17, the free resilient end 25 of which extends through a slot 18 in the socket for frictional contact with the drill bit carried thereby, so as to respectively hold the drill bits against accidental displacement from the sockets. It is to be also noted that the pivot shaft 13 is 30 located intermediate the ends of the sockets 14, but preferably closest the rear end of the sockets than the front ends thereof. Normally the sockets 14 are swung in a horizontal plane in longitudinal alignment with one another and the forward ends 35 thereof rest upon a longitudinally extending horizontally disposed rest rod 19 which rod can be supported by end brackets 20 secured in any preferred way to the lower wall 10, as shown, or to the end blocks 12.

40 In order to provide means for facilitating the selection and grasping of the desired size drill bit, I provide a plurality of selector keys 21. These selector keys 21 extend through suitable openings 22 formed in the top wall 11 and each selector 45 key 21 is connected to a selector key bar 23. The selector key bars 23 are of a resilient nature and are provided with lower rear attaching feet 24 which can be connected by means of screws or the like 25 to the bottom wall 10 adjacent to the 50 rear edge thereof. The front free ends of the selector key bars 23 are arranged directly above the rear ends of their respective drill socket 14 inward of the pivot points 13 thereof. The keys 21 are preferably arranged in staggered relation 55

as shown in Figure 1 to facilitate the application thereof to the top wall 11 and the upper faces of the keys can carry suitable indicating indicia to show the size of the drill carried by the sockets 5 for such keys.

When it is desired to select a drill bit, a key 21 carrying the desired indicating mark is depressed and the key bar 23 will bear against the inner end of its drill socket and rock this 10 socket on its pivot 13 and swing the same to an elevated position as shown in Figure 2 of the drawing. The drill bit can now be conveniently removed from the sockets, in view of the fact that the same is held in an elevated plane above 15 the other drill bits. After the drill bit has been used, the same is replaced in the socket and then swung manually to its lowered normal position.

In order to prevent the accidental swinging movement of the sockets when the same are in their lowered horizontal position or when the same are in their raised vertical position, I provide a holding relief spring 25 for each socket. This holding spring 26 is also provided with an attaching foot 27 which can be secured to the 20 bottom wall by means of a fastening element 25 utilized for the spring key bars 23. The free 25 ends of the springs normally rest under the sockets and when the socket is moved to a raised elevated position the flat rear ends thereof will 30 be engaged by the springs and thus the springs 26 will hold the same in their elevated positions.

From the foregoing description, it can be seen that I have provided a novel drill bit holder or 35 rack in which not only will the bits be kept in proper place and held against movement but means by which any desired sized drill can be readily selected and removed from said rack.

Changes in details may be made without de-

parting from the spirit or the scope of this invention, but:—

What I claim as new is:

1. A holder for drill bits of different sizes comprising a casing including a top and bottom wall, a plurality of independently pivoted sockets for receiving the drill bits, spring means engaging each socket for normally holding the sockets against swinging movement, resilient key bars mounted in the casing normally arranged about 10 the rear ends of the drill sockets in rear of the pivot points thereof, and keys for operating the resilient key bars slidable through the top wall of the casing.

2. A holder for drill bits of different sizes comprising a casing including a top and bottom wall, and end walls, a pivot rod extending between said top and bottom walls and anchored in the end walls, said pivot rod being arranged forwardly of the front edge of the top wall, a plurality of 20 drill sockets for the bits rockably mounted on the pivot rod, a rest rod attached to said casing and arranged forwardly of the casing upon which the front ends of the sockets are adapted to normally rest, leaf springs carried by said casing and engaging each socket for normally holding the sockets against swinging movement, a resilient key bar arranged above each socket and terminating in rear of the pivot rod, the top wall 25 of the casing being provided with guide openings, an operating key slidable through the openings, an operating key slidable through the openings for each key bar, whereby upon depression of any one of the keys the resilient key bar will rock its socket on its pivot, the leaf spring functioning to engage the rear end of the socket 30 and hold the same in its raised position, and means for limiting downward swinging movement of the keys.

FRANK L. JOHNSON.
